DESIGN FOR A COAT

Samuel Sandhaus, New York, N. Y.

Application February 11, 1941, Serial No. 98,925

Term of patent 3½ years

To all whom it may concern:

Be it known that I, Samuel Sandhaus, a citizen of the United States of America, residing in New York city, county of New York, and State of New York, have invented a new, original, and ornamental Design for a Coat, of which the following is a specification, reference being had to the accompanying drawing, forming part thereof, wherein,

I claim:

The ornamental design for a coat, substantially as shown.

SAMUEL SANDHAUS.
